CLAIM

The ornamental design for a water bottle, as shown and described.

DESCRIPTION

FIG. 1 is a perspective view of a water bottle, showing my new design;

FIG. 2 is another perspective view thereof;

FIG. 3 is a perspective view thereof, showing the design in open status;

FIG. 4 is another perspective view thereof, showing the design in open status;

FIG. 5 is a front view thereof, showing the design in a closed status;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

The broken lines are shown for the purpose of illustrating portions of the water bottle and forms no part of the claimed design.

1 Claim, 10 Drawing Sheets
